AUTOMATIC ELECTRIC CUT-OUT

Richard Kurz, Stuttgart, Germany, assignor to
Robert Bosch Aktiengesellschaft, Stuttgart,
Germany

Application June 2, 1932, Serial No. 615,006
In Germany June 13, 1931

1 Claim. (Cl. 200—87)

This invention relates to automatic electric cut-outs particularly for the electric systems of automobiles.

In electrical installations on vehicles an automatic cut-out switch is usually provided which connects the dynamo to the battery on the production of a certain voltage. In order that the sparks occurring on the opening and closing of the switch may not destroy the switch contacts, 10 it is known to employ a pair of preliminary contacts which are in parallel with the pair of main contacts.

The object of the present invention is to provide means whereby the preliminary contacts are 15 suddenly disengaged at a predetermined position of the armature of the switch or its return to the position of rest.

According to the invention the foregoing means may comprise a stop-plate on the armature of the 20 switch which engages the spring carrying the preliminary contact at a predetermined position on the return of the armature to the position of rest.

An example of construction of the invention is 25 shown partly in section in the accompanying drawing.

The automatic switch consists of an electromagnet *a* and an armature *b* having an arm bent at right angles to which a contact spring *c*, together with a stop-plate *d*, is riveted. The fastening rivet *e* serves at the same time as switch contact and co-operates with a stationary counter-contact *f*. A contact *g* provided on the contact spring *c* co-operates with a counter-contact 35 *h*. The pair of main contacts is denoted by *e*, *f* and the pair of preliminary contacts by *g*, *h*.

When the armature *b* is attracted by the electromagnet, the contact *g* first comes against its counter-contact *h*, so that the current flows 40 through the closed pair of preliminary contacts *g*, *h*. When the armature is further attracted, the pair of main contacts *e*, *f*, is then closed.

On the return of the armature *a*, the pair of main contacts *e*, *f* is first opened, the current still 45 flowing through the closed pair of preliminary contacts *g*, *h*. On the further backward movement of the armature *a*, the stop-plate *d* suddenly

lifts the contact spring *c* from the contact *h*, whereby sparking and the burning of the contacts is diminished. The contact spring *c* cannot be considerably heated by the sparking arising from a light contacting of the contacts in comparison with previous forms of construction in which the contact spring might be so strongly heated by the contact sparking that it loses its predetermined tension.

As can be seen from the drawing, the stop-plate 10 *d* can be fastened in a simple manner together with the contact spring *c* to the armature *a*.

I declare, that what I claim is:

In an electric switch of the electromagnetic type, the combination with an electromagnet and 15 a pivoted armature having a portion in adjacent opposition to a pole of said electromagnet for actuation of said armature by said electromagnet and another portion disposed to one side or laterally of said electromagnet out of alignment 20 with the polar axis thereof, of a pair of stationary contacts entirely to said one side of said electromagnet and with both contacts of said pair on the same side of said laterally-disposed portion of said armature, a main contact carried by said 25 laterally-disposed portion of said armature and cooperating with one of said stationary contacts, a leaf spring carried by said laterally-disposed portion of said armature, a preliminary contact secured to said leaf spring at a point thereon laterally spaced from said electromagnet and cooperating with the other of said stationary contacts, 30 said armature being movable by said electromagnet from a position of rest to bring said preliminary and main contacts into engagement with 35 said stationary contacts and said armature automatically returning to said position of rest upon de-energization of said electromagnet, and a rigid plate secured to said laterally-disposed portion of 40 said armature and engaging said spring to abruptly disengage said preliminary contact from its cooperating stationary contact on said return movement of said armature, said main contact being so formed as also to constitute means securing said leaf spring and plate to said armature. 45
